COMBINED TAP AND SURFACING
IMPLEMENTAlfred E. Dennis and Irvin L. Dennis,
Oskaloosa, Kans.

Application September 30, 1935, Serial No. 42,782

1 Claim. (Cl. 10—140)

Our invention relates to improvements in combined taps and surfacing implements.

It relates particularly to an implement including a tap and a cutting tool arranged to have the tool cut the surface of a body around a threaded hole in which at the time the tap is fitted.

It is adaptable for reaming out the threaded hole in which a spark plug has been fitted, and for cutting and cleaning the surface around the hole to enable the spark plug, which is to be inserted into the hole, to have good electrical connection with the engine body.

One of the objects of our invention is to provide a novel implement of the kind described in which the cutting tool is adapted for free revolution on the tap and for movement into and out of its cutting position longitudinally on the tap, whereby the cutting tool may be withheld from its cutting position until the tap has been revolved to a position in which it will have cleared the threaded hole, following which the cutting tool may be independently revolved on the tap an amount sufficient for clearing the surface around the hole to the extent desired.

A further object of our invention is the provision of novel means by which the cutting tool may be revolved independently of the tap or simultaneously with it.

Still another object of our invention is the provision of a novel implement of the kind described, which is simple, cheap, durable, not likely to get out of order, which is easy to operate and which is efficient in its operation.

The novel features of our invention are hereinafter fully described and claimed.

In the accompanying drawing which illustrates the preferred embodiment of our invention,

Fig. 1 is a central longitudinal sectional view of our improved implement, showing the tap operatively mounted in the threaded hole in the engine body and locked to the cutting tool, the latter being shown out of its operative position.

Fig. 2 is a vertical view partly in side elevation and partly in vertical section, showing the tap mounted in the threaded hole in the engine body and the cutting tool revolvable on the tap and in the cutting position, with the handle disposed in the upper hole in the cutting tool and disengaged from the tap.

Fig. 3 is an end view of the implement.

Fig. 4 is a side view of the cutting tool, with the handle in the tool and broken away.

Fig. 5 is an end view of what is shown in Fig. 4.

Similar characters of reference designate similar parts in the different views.

1 designates the shank of the tap which is provided adjacent to one end with a threaded peripheral cutting portion 2, which is intersected by spaced apart longitudinal slots 3, which at their inner ends communicate with a longitudinal central hole 4 extending from the adjacent end, and which is adapted to receive cuttings made by the cutting edges 3' of the threads that are intersected by the slots 3.

A plug 5 is removably fitted in the outer end of the hole 4 to prevent the cuttings falling from the hole 4 into the engine body during the cutting operation of the tap.

Mounted and adapted for free revolution on the tap shank 1 is a tubular cutting tool 6, which is also adapted for longitudinal sliding movement on the shank 1.

The end of the cutting tool 6 which is adjacent to the threaded portion 2 of the tap is provided with cutting edges 7.

To limit the longitudinal movement of the cutting tool 6 on the shank, a transverse stop screw 8 is fitted in a threaded hole in the cutting tool 6 adjacent to the cutting edges 7, the screw extending into an annular peripheral groove 9 in the shank 1.

For rotating the tap in its cutting operation, and at the same time holding the cutting tool 6 out of its cutting position, the tap shank 1 is provided with a transverse hole 10 therethrough which is adapted to align with a transverse hole 11 extending through opposite walls of the cutting tool 6. A handle comprising a rod 12 is adapted for insertion through the aligned holes 10 and 11 and to project from opposite sides of the cutting tool 6, as shown in Fig. 1.

With the parts so assembled, the threaded portion 2 of the tap is screwed into a spark plug threaded hole 13 in an engine body 14, as shown in Fig. 1, during which operation the cutting edges 3' of the threads of the tap cut away rust and scale which may have formed in the plug hole 13, thus providing a clean conductive metal contacting surface for grounding the spark plug when it is screwed into the engine body.

After the spark plug hole 13 has thus been cleaned, the handle 12 is removed from the aligned holes 10 and 11 and is inserted through a hole 15 which extends clear through the cutting tool 6 in a transverse plane which is above the plane of the hole 11, and which is above and spaced from the upper end of the tap shank 1 when the cutting

tool 6 is lowered to its lowest position on the shank 1.

The cutting tool 6 is then slid downwardly on the shank 1 until the cutting edges 7 of the cutting tool rest on the surface of the engine body 14, encircling the hole 13 in the engine body 14, as shown in Fig. 2. The cutting tool 6 is then revolved in the proper direction for cutting on the shank 1 by the handle 12, downward pressure being applied to the cutting tool, the cutting edges 7 of which will remove rust and scale from the surface of the engine body adjacent to and encircling the hole 13, so that a clean conductive contact surface is provided against which the spark plug, when inserted in the hole 13, may bear.

Upon removing the handle 12 and screwing the screw 8 out of the annular groove 9, the cutting tool 6 may be removed from the shank 1, and 20 with the use of the handle 12 either the tap or cutting tool may be separately used.

After the tapping and surfacing operations, the cutting tool is slid upwardly, the handle 12 having been removed, until the hole 11 aligns 25 with the hole 10. The handle 12 is then reinserted in the aligned holes 10 and 11 and the tap unscrewed out of the hole 13. The plug 5 is then removed from the hole 4 and the cuttings therein are removed, following which the plug is again 30 inserted in the hole 4.

By having the slots 3, which communicate with the end hole 4 in the tap, intersecting, as shown, a number of the threads of the cutting portion 2, 35 a number of cutting edges 3' are provided and ample spaces are provided for receiving cuttings as well as reducing the frictional resistance to the inward screwing of the tap.

By having the interior diameter of the cutting end portion of the surfacing tool 6 greater than 40 the diameter of the threaded portion 2 of the tap,

as shown, the threaded portion 2 of the tap may have the upper part thereof enter the tool 6, so that the cutting edge 7 may cut a surface above which the threaded portion at the time is projecting, as in Fig. 2. This is of importance when 5 the hole that is being tapped is too shallow to receive the entire threaded portion 2 of the tap.

The implement comprising the tap 1 and surfacing tool 6 may be employed for removing deposits in and around a threaded hole, as one which 10 has contained a spark plug, or the tool may be employed to have the cutting portions 3' and 7 respectively cut the metal to thread the hole 13 and to cut the metal around the hole.

Many modifications of our invention, within 15 the scope of the appended claim, may be made without departing from the spirit of our invention.

What we claim is:—

A combined tap and surfacing implement including a tap having a peripheral cutting portion, a tubular surfacing tool having at one end a cutting edge and revoluble on said tap and movable thereon to and from a position in which it is adapted to surface a portion of a body encircling a hole in said body in which said tap at the time is operatively engaged, said tap having therethrough a transverse hole, said tool having two transverse holes therethrough, the one nearer said cutting edge being adapted to align with said hole in said tap when said cutting edge is out of its cutting position, the other hole in said tool being disposed out of transverse alignment with the tap when said tool has its cutting edge in the cutting position, and a handle member removably insertable through said hole in the tap and through the two holes in said tool. 20 25 30 35 40
